UNITED STATES PATENT OFFICE.

MERRITT GALLY, OF NEW YORK, N. Y.

MECHANICAL MUSICAL INSTRUMENT.

SPECIFICATION forming part of Letters Patent No. 279,933, dated June 26, 1883.

Application filed October 9, 1882. (No model.) Patented in England July 11, 1882, No. 3,291.

To all whom it may concern:

Be it known that I, MERRITT GALLY, of New York city, in the county and State of New York, have invented a new and useful Improved Mechanical Musical Instrument, (for which I have obtained Letters Patent of Great Britain, through Mr. George Downing, No. 3,291, A. D. 1882, July 11,) of which the following is a specification.

10 The object of my invention is to produce a small and compact mechanical musical instrument, easily portable, possessing a good quality of tone, with great volume and power.

In the accompanying drawings, Figure 1 is 15 a sectional view of the instrument, the construction of the case, the bellows, wind-chest, reed-pipe, reflector, the operating music-sheet, with its rollers, and the driving motor-shaft and connections of the instrument. Fig. 2 is 20 a side view of the rolls, with journal-bearings and the driving-crank of the instrument. Fig. 3 is a perspective of the comb of pipes, connected together to facilitate adjustment and removal. Figs. 3^a and 3^b are modifications 25 of form of pipes shown in Fig. 3. Fig. 4 is a sectional view, showing construction of double reed-tubes, wind-chest, &c. Fig. 5 is a plan of the upper part of the instrument; and Fig. 6 is a longitudinal section of the wind-chest 30 and pendent reed-tubes.

Small mechanical musical instruments as ordinarily constructed are very defective as to volume, power, and sustaining quality of tone, especially in performing music in slow time, 35 as with the ordinary construction of the reed-action the necessarily small bellows is entirely inadequate, unless operated so rapidly as to give the music a jerky and improper rendering. The instrument shown in the drawings 40 is not necessarily larger than an ordinary "orguinette," and yet its peculiar and novel construction secures a tone of at least fourfold volume and power, a sustaining-power sufficient for the performance of any kind of music, 45 and the carrying quality of a large pipe-organ. It also possesses a much more desirable and pleasing quality of tone than can be secured by the ordinary use of reeds. The instrument represented in the drawings is a 50 reed-pipe "organetto" operated by means of a perforated music-sheet, and on account of its

powerful and peculiar tone may properly be called a "clarioncello."

In Fig. 1, C D E represent the bellows of the instrument, which are operated by means of an ordinary crank-shaft, J, which also turns the music-sheet take-up roll H. The bellows are of ordinary size for an orguinette, and would not be sufficient for a sustaining-power of tone were it not for the peculiar construction of the 55 reed-tubes and air-chest, as shown, which secures a full tone with only about one-third the ordinary consumption of air.

The novel construction of the tube-board and air-chest is shown in Fig. 1, and also in 60 Fig. 4, the ordinary construction being shown in Fig. 4 in dotted lines for illustrating the comparative action of the two systems and the improvement of the new over the old.

In ordinary manual reed-organs the tubes 65 for the reeds are much shorter than the reed-blocks to which the tongues are attached, the butt of the reed being allowed to project beyond the mouth of the tube. By this construction the air is brought to the tongue in a 70 direction at an angle to the plane of the reed, which secures the best tone. This feature of construction and its advantages have been 75 overlooked by those making instruments to be operated by perforated music-sheets passing 80 over the end of the reed-tubes, and the tubes have been elongated to cover the entire reed, as shown by the dotted lines, Fig. 4, thus producing a harsh and unpleasant tone. In my 85 improved construction (shown by the section-lines) I make the tube e of as near regular organ length as possible, and cut away the butt of the reed to allow the music-sheet to pass over the opening of the tube without obstruction. I then enlarge the tube e internally and 90 contract the outlet more than its mouth-opening, in order to break the tension of the current of air and allow the tongue of the reed free opportunity for vibration. In the old construction (shown by the dotted lines) the opening through the reed into the air-chest S is 95 from the line 1 2 to the end of the reed, nearly the entire length of the tongue, producing great waste of air and holding the tongue in a constant tension-current, unfavorable to good 100 results as to character of tone. I confine the current of air to the extreme end of the vibrat-

ing tongue. I then place behind the reeds a second set of tubes, *a*, similar to tubes *c*, and contract their outlets *n*. The current of air through the reeds is thus deflected, taking the 5 direction shown by the curved lines, and thus reacting upon the reed-tongue secures the best results with a small consumption of air.

In order to economize space and secure as large an air-chest as possible, and to still further improve the quality of the tone of the reed, I hang the compound tube-board within the chest *S T*, surrounding the tube-board with air which is under tension by the action of the bellows. In order that the tension of the air 15 in the chest *S T* shall remain as even as possible and not be disturbed by the movement of the exhausters of the bellows, I give the chest as large capacity as possible and contract as much as practicable the trunk *t*, leading to 20 the bellows. In the drawings the reed is shown in position for exhaust-bellows; but the construction is equally valuable with reversed reed and pressure-bellows.

By means of the construction thus far described I secure a full, clear, and sustaining tone to the reeds, and the next thing desirable is to increase the power and volume of tone and secure the carrying quality of an ordinary pipe-organ. The pitch of an ordinary organ- 25 pipe is determined by its length, the C-pipe, beginning the diapason range, being four or eight feet long, which would make the pipe for the lowest note of an organetto, adding the necessary length of foot, nearly three feet in 30 length. A regular reed-pipe of an organ corresponds in pitch-length to the pitch of the reed, and requires a still longer foot. Such pipes could not be used on an ordinary organetto. By means of a novel construction 35 shown in Fig. 1, I preserve the pitch of the reed without a corresponding pitch-length to the pipe, and at the same time secure the desired volume, power, and carrying quality of tone. In an ordinary reed-pipe the reed is in 40 closed within the foot of the pipe, and the pipe speaks only through its bell end, like an ordinary trumpet. Instead of this construction, I open a mouth, *r*, at the foot of the pipe and divide the vibrating air, one part passing 45 through the pipe and the other part coming directly from the reed. In this respect my invention differs materially, not only from the ordinary reed-pipe with inclosed reed, but also from the devices of Goodman, Patent No. 55 133,851, and Vogel, No. 147,202, the one intentionally avoiding the division of air necessary to the results produced in my invention, and the other preventing such results by the use of a covered pipe. In my invention I use 60 a pipe with open flue and place the reed-cell in such position in respect to the flue and make the opening at the foot of the pipe small enough to secure a positive division of the vibrating air, which produces not only a peculiar tone, but the "carrying" effect of a regular flute-mouth organ-pipe. By this means I pre-

serve the pitch of the reed without a corresponding pitch-length of pipe, and find that a very small pipe, *R*, will produce the proper modifying effect as to volume, power, and carrying quality. As the foot of the pipe is open, it enables me to pass the music-sheet through the opening between the reed and pipe proper. With this construction I also find that either pressure or exhaust air can be advantageously used. 70 75

In order to make the construction as compact as possible, I make a comb of these small pipes, as *R*, Fig. 3, and, as any pair of the reeds of the range seldom, if ever, speak together, I use only one pipe in this particular instrument to each pair of reeds. In instruments where space is not limited I use a pipe for each reed. To secure a proper speaking of the reeds should any pair speak together, I open the side 80 85 equally with the front of each pipe, which enables the reed to speak into the next flue. I imitate the tone of different instruments with these short pipes by varying their shape very much in the same manner as with the regular 90 95 reed-pipe. For example, the trumpet tone is secured by the shape shown in Fig. 3^a, and the clarionette by the shape shown in Fig. 3^b. I make different combs composed of pipes of these or other shapes for imitating any desired instrument, and with the end flanges, *t*, made to fit sideways in the frame-work of the instrument, as shown in Fig. 5, I can interchange the combs at will, thus producing a variety in kind of music with very little expense. 100

In connection with the comb of pipes *R*, I also use the compound reflector *Y* for modifying and varying the quality of tone at will. Tones vary in quality as reflected from planes placed at different angles, and combined reflections give the most pleasing results. I therefore use for this simple instrument a hinged reflector with compound reflecting-faces, as shown, which in different positions produces different and desirable results as to 105 110 115 quality of tone.

In operating this instrument, as shown in Figs. 1 and 5, the music-sheet *b* is rolled from roller *I*² onto take-up roller *H* by means of crank *K*, which also works the bellows of the 115 instrument. The roller *H* is mounted in bearings which bring its gear directly in connection with the driver of the driving crank-shaft *J*, and is driven by either friction or tooth-gear, as desired. Roller *H* is furnished with 120 two sets of journal-bearings, *N* and *P*. When the journals are in the bearings *P* the roller is in driving position as to the driving-shaft *J*; but when the roller is lifted into its bearings *N* it moves freely, and the music-sheet may 125 be rewound by means of crank *L* and removed from the instrument to be replaced by another piece of music. The flanges of roller *I* are permanently attached to the journals of the instrument, as shown in Fig. 5, and the roll is 130 removed by drawing one of these flanges to one side against the action of spring *Q*. The

rollers fit into the flanges, which are supplied with splines for turning the roll.

A sectional plan of the compound tube-board and wind-chest is shown in Fig. 6. The 5 double tube-board *e a* is formed of two ordinary tube-boards, glued back to back, with a thin partition between them, through which partition are cut the openings for the air-passages through the reed.

10 In constructing the instrument, the bellows, reed-chest, and all the working parts are attached to the top piece, *A*, which piece is screwed to the body of the case. By removing the screws of the top piece it can be lifted 15 from the case with the entire instrument intact for repairs or adjustment. This construction is of great utility.

In the foregoing specification I have described only what was necessary to the proper 20 construction of the little instrument shown, reserving a theoretical exposition of the principles introduced in the construction and operation of the reed-chest, reed-pipe, &c., and their general application for another specification.

25 I claim—

1. The reed-cells, in combination with supplemental cells, the latter for deflecting the operating currents of air, the supplemental 30 cells having an opening for the passage of air through the reeds, and another constricted opening connecting directly with the wind-chest of the instrument.

2. The combination, with the reed-cells, of 35 supplemental cells having their ducts which

connect with the wind-chest placed at a distance from the outer wall of the supplemental cell, to produce a reflex movement of the operating current of air.

3. The reed-pipe with open flue provided 40 with a mouth or opening, of a size substantially as described, at or near the junction of the pipe proper with the reed-cell, for dividing the tone of the reed, so that a part of the tone shall pass directly to the open air and a 45 part through the pipe.

4. The combination, with the reed-chest, of an independent comb of pipes constructed to be readily removed and adjusted in position, substantially as specified. 50

5. The combination, with the sound-producing devices of a musical instrument, of a compound reflector having two or more reflecting-faces, located to receive and reflect the sound, substantially as described, to give to 55 the tone a combination of reflections.

6. The combination, with the sound-producing devices of a musical instrument, of the compound reflector, located to give to the tone a combination of reflections, and made adjustable for changing the angles of reflection. 60

7. The combination, with short reed-cells, over or outside of which a perforated music-sheet passes, of reeds having short butts, or having the ordinary reed-butts cut away, substantially as and for the purpose specified. 65
